SCAFFOLD BRACKET

Filed Dec. 9, 1920

Joseph F. Graff, Inventor

By Mason Farnick Lawrence,
Attorneys

UNITED STATES PATENT OFFICE.

JOSEPH F. GRAFF, OF MILWAUKEE, WISCONSIN.

SCAFFOLD BRACKET.

Application filed December 9, 1920. Serial No. 429,433.

To all whom it may concern:

Be it known that I, JOSEPH F. GRAFF, a citizen of the United States, residing at Milwaukee, in the county of Milwaukee and 5 State of Wisconsin, have invented certain new and useful Improvements in Scaffold Brackets; and I do hereby declare the following to be a full, clear, and exact description of the invention, such as will enable 10 others skilled in the art to which it appertains to make and use the same.

This invention appertains to folding scaffold brackets and means for securing such and other brackets to the wall of a building 15 or the like.

The objects of the invention are to produce a bracket which may be collapsed into compact space and easily transported from job to job, also to construct a safe builder's bracket 20 which may be quickly, easily and strongly attached to the wall of a building and quickly and easily removed therefrom.

The invention consists in the particular construction and arrangement of parts as 25 more particularly set forth in the following description.

In the accompanying drawings in which similar reference characters designate similar parts in all of the several views:

30 Figure 1 is a side elevation of my improved bracket shown in position upon a wall;

Figure 2 is a horizontal section through a fragment of wall on the line 2—2 of Figure 35 1 showing an upper plan view of the bracket-attaching stirrup and a fragment of the bracket connected therewith;

Figure 3 is a perspective view of the bracket detached from the wall and from 40 the supporting stirrup and in process of being folded.

Figures 1 and 2, respectively, indicate a vertical and a horizontal section through the wall of a building with one of my improved 45 brackets attached. In said figures A indicates a stud, B a sheathing, C an air space and D a veneer of brick or the like. This illustration of a wall is diagrammatic only and serves to illustrate the mode of application 50 of my improved bracket to the wall of a building.

As a means for fastening the improved bracket to a wall I have devised a stirrup 1. This stirrup is made, preferably, of wrought 55 plate or strap iron or steel of U-shaped form,

with parallel side arms spaced apart a sufficient distance to enable it to embrace a stud A and of sufficient length to extend completely through the wall of a building. The length of the arms of the said stirrup 1 may 60 of course be varied at will. In the upper edges of the parallel arms of said stirrup, inclined slots or notches 2 are formed. These notches are preferably spaced apart so as to adapt the stirrup to be used on walls 65 of different thicknesses. In Figures 1 and 2 I have illustrated three sets of notches or slots 2 which incline from the upper edges of the arms of the stirrups downward and rearward. The outer notch, as shown in the illustration, is at such a distance from the connecting member 1^a, which joins the two parallel arms of the stirrup, as to adapt the stirrup to be used on a building with a brick facing or veneer. On an ordinary frame 70 building one of the other sets of notches would be used. The purpose of the inclined slots or notches is to sustain a bracket of the form disclosed in this application, said bracket carrying a bolt 15 adapted to seat in 75 a pair of the slots or notches, the weight of the bracket tending to force the bolt downward in the inclined slot and draw the bracket close to the wall, the heavier the 80 weight upon the bracket the greater the 85 tendency of the bracket to hug the wall.

The improved bracket consists of three members 10, 11 and 12. The member 10 is slightly longer than the member 11, said members being pivoted together at one end. 90 The member 12 extends between the other ends of said members 10 and 11 when the bracket is assembled in form for use, said bracket then constituting in outline substantially a right angled triangle, of which 95 members 10 and 11 define two of the sides and the member 12 the hypotenuse.

The members 10, 11 and 12 are formed of channel irons of different sizes in cross section. The largest cross section is in the member 12, the second largest in the member 10 and the smallest in the member 11. The difference in size is such that the member 11 may fold within the channel of the member 10 and the members 10 and 11 may fold 105 within the channel of the member 12. The members 10 and 12 are preferably connected together at one end by a bolt or rivet 13 so that they may fold with respect to each other. One end of the member 11 is pivoted to the 110

other end of the member 10 by a screw bolt 15, said bolt being long enough to project considerably on each side of the member 10 the projecting portions being adapted 5 to seat within a pair of slots or notches 2 in the stirrup 1. Said bolt 15 is provided with washers and a suitable nut, or other means to prevent endwise displacement, as 10 illustrated. The member 11 pivoted on the bolt 15 is adapted to fold and lie between the sides of the member 10, said member 11 being shorter than the member 10 and clearing the bolt 13. At 14 is shown a bolt adapted 15 to be detachably passed through registered perforations 16—17 in the outer ends of the members 11 and 12. This bolt may have a cotter pin in one end or, if preferred, be provided with a nut, and when said bolt is passed through the perforations in the 20 member 11 and the member 12, the said members 10, 11 and 12 will be connected in the outline of a right angled triangle and will form a rigid bracket. When now the bolt 15 rests in a pair of slots 2 in the stirrup 25 1 the back of member 10 and the lower end of the member 12 will bear against the face of the wall of the building and constitute a rigid scaffold bracket. Scaffold planks may be bolted to the top of member 11 30 through bolt holes 18.

Owing to the fact that the members 10 and 11 are of different lengths either member 10 or 11 can be utilized for receiving the 35 planks or boards of the scaffolding. Thus, by this bracket, scaffolds of different widths may be easily provided.

To detach the brackets it is only necessary to push or lift them upward whereupon they will be easily released from the inclined 40 slots 2. When thus released the bolt 14 may be removed and the bracket folded as indicated in Figure 3 until all three members 10, 11 and 12 lie approximately parallel 45 making a convenient bracket to be transported from place to place.

The stirrups 1 may be knocked rearward and quickly detached from the building wall,

transported to another place and very quickly placed in position.

The described bracket is simple and 50 strong; the U-shaped stirrup and the connection of the bracket thereto renders the bracket perfectly safe and yet susceptible of being attached and detached with the utmost 55 simplicity. The members of the bracket being of channeled shapes of different sizes, makes the bracket extremely strong and light and susceptible of being folded into a compact article for convenience of transportation. The relative proportions of the 60 channel members at right angles to each other are such as to render the bracket reversible for different widths of scaffolding and at the same time facilitate the folding. By reason of the described connections 65 comprising the inclined slots 2 of the stirrup which receive the bolt 15 the bracket is caused to hug the wall more tightly the more weight there is placed upon it.

Having described my invention in such 70 manner as to enable those skilled in the art to which it appertains to make and use the same, what I claim and desire to secure by Letters Patents of the United States is:

1. A support for scaffolding brackets comprising a U-shaped stirrup having its parallel arms provided with slots extending downward from their upper edges and inclined 75 rearward toward the member connecting said parallel arms.

2. The combination of a U-shaped stirrup adapted to embrace a stud, said stirrup having slots extending from the upper edges of its parallel arms, at an inclination downward and rearward toward the member connecting said parallel arms, a bracket having a scaffold supporting member and a member adapted to rest against a wall, and a bolt projecting laterally from each side of said bracket adjacent the junction between 90 said members, said bolt adapted to be seated in said inclined slots.

In testimony whereof I affix my signature.
JOSEPH F. GRAFF,
